(57) **CLAIM**

I claim the ornamental design for a tool handle, as shown and described.

DESCRIPTION

FIG. 1 is a perspective view of the ergonomic tool handle of my design;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is an opposite side view thereof.

1 Claim, 2 Drawing Sheets
